CLAIM

The ornamental design for an ammunition box insert block, as shown and described.

DESCRIPTION

FIG. 1 is a top isometric exploded view of an ammunition box including an insert block according to the present invention.

FIG. 2 is a top isometric partially exploded view of the ammunition box of FIG. 1.

FIG. 3 is a top isometric unexploded view of the ammunition box of FIG. 1.

FIG. 4 is a top view of the ammunition box of FIG. 1.

FIG. 5 is a top isometric view of the insert block of the ammunition box of FIG. 1.

FIG. 6 is a top view of the insert block of FIG. 5.

FIG. 7 is a bottom view of the insert block of FIG. 5.

FIG. 8 is a front view of the insert block of FIG. 5. The rear view is identical.

FIG. 9 is a first side view of the insert block of FIG. 5. The opposite side view is identical; and,

FIG. 10 is a cross-sectional view through the insert block of FIG. 5, taken along line 10-10 of FIG. 6.

The area between the symbolic break lines shown in dash-dot-dot-dash lines forms no part of the claimed design.

The dot-dot broken lines depict portions of the ammunition box that form no part of the claimed design.

The broken lines depicting bullet cartridges represent environment that forms no part of the claimed design.

The dot-dash vertical broken lines in the exploded views indicate where separate parts fit into one another and form no part of the claimed design.
